UNITED STATES PATENT OFFICE.

GUSTAV MENZ, OF BERLIN-CHARLOTTENBURG, GERMANY, ASSIGNOR TO SIEMENS-SCHUCKERTWERKE GESELLSCHAFT MIT BESCHRÄNKTER HAFTUNG, OF BERLIN-SIEMENSSTADT, GERMANY, A CORPORATION OF GERMANY.

RUNNER BLADE FOR STEAM TURBINES.

Application filed February 12, 1927, Serial No. 167,741, and in Germany February 17, 1926.

My invention relates to the runner blades for steam turbines.

It is well known to machine the blades of runners or rotor wheels of steam turbines 5 out of a solid ring placed upon and bolted to the body of the runner. The covering band is also constructed as a solid ring and fitted upon the blade ring.

In the hitherto employed constructions 10 forces set up by heat stresses are liable to be transferred from the runner to the blade ring and vice versa, owing to the solid jointing of the two parts. As this is apt to lead to distortions of the parts the operation of 15 the turbine might become endangered thereby.

The object of my invention is to eliminate this drawback. My invention consists in mounting the blade carrier ring upon the 20 runner wheel by means of one or a plurality of rings fitted into recesses and against the runner and the blade carrier in axial direction. In this way the runner and the blade carrier are able to sustain the stresses 25 prevailing in them without one part affecting the other.

In the drawing affixed hereto an embodiment of my invention is shown by way of example represented in

30 Fig. 1, a cross-section through part of a turbine containing two of my improved runner wheels, on one of them being shown the covering band and on the other the manner of fixing the blade ring,

35 Fig. 2, a sectional plan of Fig. 1, and

Fig. 3, a longitudinal section through part of a runner wheel.

Like parts are indicated by like numerals in all the figures of the drawing.

40 Referring to Fig. 1, it will be observed that the runner wheel 1 is provided upon its circumference with a central outer peripheral projection or flange 8 the diameter of which corresponds with the inner diameter 45 of the blade ring 2. This blade ring is likewise provided with an inner peripheral projection or flange 9 of the same diameter as the flange 8. To prevent an axial displacement of the blade ring upon the runner, rings 4 and 5 are placed at both sides 50 into the recesses of the runner wheel and the blade ring and against the flanges 8 and 9 and forced against the flanges by

screws or rivets 7. A lateral displacement of the blade ring upon the runner wheel is 55 thus effectively prevented. It will be understood that it is not absolutely necessary that locking rings 4 and 5 should be provided at both sides of the flanges, but the flange 9 upon the blade ring 2 might at one 60 side project beyond the flange 8 of the runner so that only one locking ring would then be necessary.

As shown on the left-hand runner wheel in Fig. 1 and in plan in Fig. 3, the covering band 3 is fixed to the blade ring 2 by radial bolts 6 so as to prevent relative motion. The bolts 6 must not be subjected to tangential stresses as otherwise they might 70 be shorn off.

To prevent the blade ring 2 mounted upon the runner wheel as specified above from creeping upon the wheel, radial keys or wedges 10, Fig. 3, are inserted between the two parts which prevent a relative displacement in a circumferential direction. 75

Various modifications and changes may be made without departing from the spirit and the scope of the invention, and I desire, therefore, that only such limitations shall 80 be placed thereon as are imposed by the prior art.

I claim as my invention:—

1. In a rotor for steam turbines, the combination of a runner, a blade ring mounted 85 on the periphery of said runner, runner blades integral with said blade ring, at least one retaining ring for said blade ring, there being an annular recess extending over a portion of the blade ring and of the runner 90 for receiving said retaining ring, and means for pressing said ring against the blade ring and the runner to hold the former in place, whereby the transmission of stresses between the runner and the blade ring is prevented. 95

2. In a rotor for steam turbines, the combination of a runner, a blade ring mounted on the periphery of said runner, runner blades integral with said blade ring, a retaining ring on each side of the blade ring 100 for said blade ring, there being an annular recess on each side of the runner, extending over a portion of the blade ring and of the runner for receiving said retaining rings, and bolts holding said retaining rings together, whereby the blade ring is secured 105

to the runner in axial direction and whereby the transmission of stresses between the runner and the blade ring is prevented.

3. In a rotor for steam turbines, the combination of a runner, a blade ring mounted on the periphery of said runner, runner blades integral with said blade ring, a retaining ring on each side of the blade ring for said blade ring, there being an annular recess on each side of the runner, extending over a portion of the blade ring and of

the runner for receiving said retaining rings, and bolts holding said retaining rings together, whereby the blade ring is secured to the runner in axial direction and whereby the transmission of stresses between the runner and the blade ring is prevented, and transverse keys engaging said blade ring and said runner for securing the blade ring to the runner in circumferential direction. 15 20

In testimony whereof I affix my signature.
GUSTAV MENZ.
